EYEGLASS CONSTRUCTION

George E. Nerney, Attleboro, Mass., assignor to
Bay State Optical Company, Attleboro, Mass.,
a corporation of Maine

Application January 30, 1934, Serial No. 708,948

4 Claims. (Cl. 88—44)

This invention relates to eyeglass construction and more particularly to a frame known as an "Oxford" frame.

One of the objects of this invention is to provide an eyeglass construction which is simple, thoroughly practical and durable in use. Another object is to provide a construction of the above character which will be inexpensive in manufacture and which may be easily and rapidly assembled. Another object is to provide a construction of the above character which will be light, graceful and pleasing in appearance. Another object is to provide a construction of the above character in which the frame may be folded into a compact form and which may be readily released therefrom into an open position. Another object is to provide a construction of the above character adequately strong to withstand repeated opening and closing. Another object is to provide a construction of the above character in which the frame may be folded into a closed position without fouling certain of the parts thereof. Other objects will be in part obvious and in part pointed out hereinafter.

The invention accordingly consists in the features of construction, combinations of elements and arrangements of parts as will be exemplified in the structure to be hereinafter described, and the scope of the application of which will be indicated in the following claims.

In the accompanying drawing, in which is shown one of the various possible embodiments of my invention,

Figure 1 is a rear elevation of a frame having the features of my invention embodied therein;

Figure 2 is a top plan view of the frame shown in Figure 1;

Figure 3 is a rear elevation of the frame shown in Figure 1 folded into closed position, and

Figure 4 is an exploded perspective view, partly broken away, of a portion of the frame shown in Figure 1.

Similar reference characters refer to similar parts throughout the several views of the drawing.

As conducive to a clearer understanding of certain features of this invention, it might here be pointed out that oxford frames have a number of inherent defects which materially detract from their durability, easy operation, and graceful appearance. Some of the frames, in order to partially overcome inherent weaknesses of construction, are so reenforced as to appear bulky or clumsy while being worn. One of the greatest defects in frames of this type appears when they

are folded into their closed position. When thus folded, one lens must of course pass over and ultimately register with the other lens. In order to do this, one of them must be forced out of line by twisting the bridge or other parts of the frame. It is clear then that repeated closing will soon weaken various parts of the frame to a point where they will be damaged beyond repair. A further risk of scratching the lens surfaces as they pass over each other during folding is also 10 encountered. Where nose guards are secured to the rims of these frames, as is often the case, they often foul during the closing of the frame, thus to further weaken the whole assembly. One of the objects of this invention is to provide an 15 oxford frame in which the above difficulties as well as numerous others are rectified.

Referring now to Figure 1, there is shown a frame having a pair of rims 10 and 11 completely encircling and holding in position a pair of lenses 12 and 13. Rims 10 and 11 may be of any suitable construction and are split at the points 14 and 15 in order that the lenses may be disposed therein.

Preferably I provide a suitable bridge 16 or the like to bridge the space between rims 10 and 11 and maintain them in proper relation to one another. Bridge 16 is secured to rims 10 and 11 by a pair of fittings generally indicated at 17 and 18 respectively which will be more fully described 30 hereinafter.

I provide a pair of nose guards generally indicated at 19 and 20 having arms 19a and 20a secured, as by soldering for example, to the end portions of the bridge 16. As nose guards 19 and 20 are substantially similar in construction, nose guard 20 only will be described in detail. With reference to Figures 2 and 4, arm 20a of nose guard 20 extends rearwardly of bridge 16 and then a portion 20b extends downwardly. A 40 curved portion 20c extends a short distance in substantially parallel relation with bridge 16 and then curves rearwardly therefrom to form a nose-engaging portion 20d.

As more clearly shown in Figure 2, all portions 45 of nose guard 20 with the exception of arm 20a are spaced to the rear of the plane of rims 10 and 11. As both nose guards 19 and 20 are immovably secured to bridge 16, the danger of their fouling with one another or with either of the 50 rims when the frame is folded into a closed position is obviated, all as will be more fully described hereinafter.

Bridge 16 is preferably of a slightly resilient character in order that nose guards 19 and 20 55

may be securely fitted to the wearer's nose without excessive or uncomfortable pinching. Extending from each end of bridge 16, I preferably provide respective pairs of lugs 16a and 16b on the right (Figure 2) and 17a and 17b on the left hand end thereof. As both pairs of lugs are substantially similar in construction, lugs 16a and 16b as well as the parts associated therewith will be described in detail.

10 Lug 16a is provided with a bore 16d preferably threaded and coextensive with the thickness of the lug and has formed therein a notch 16c or the like, while lug 16b is also provided with a bore 16e preferably larger in diameter than bore 16d and also coextensive with the thickness of lug 16b.

Fitting 18 is preferably secured to rim 11 at a point near the abutting ends thereof, and includes a barrel portion 21 or the like having a suitable bore extending therethrough coaxial with bores 16d and 16e; suitably formed in one end of barrel 21 is a slot 21a. Lugs 16a and 16b fit over the opposite ends of barrel 21 and disposed within the barrel is a spring 22 having its end 22b in slot 16c and its end 22a in slot 21a. Extending through bore 16e, spring 22 and threaded into bore 16d is a screw 23. The head of screw 23 is disposed within bore 16e of lug 16b in a flush position. Accordingly, it will be seen that I have provided a thoroughly practical spring joint, the spring 22 being of suitable strength to bias rim 11 toward an open position or that position shown in Figure 1.

It will now become clear that spring 22 forces rim 11 to pivot about screw 23 as an axis to assume the above-mentioned open position until a stop 24 secured to barrel 21 abuts against the top of portion 20a of nose guard 20. Also during this pivotal movement of rim 11, it as well as its connected parts is completely out of engagement with noseguard 20. As more clearly shown in Figure 2, rim 11 is secured to fitting 18 at one end thereof hereinafter called the "front" end. Rim 10, however, is secured to fitting 17 at the "rearward" end thereof with respect to the position of fitting 18. By thus securing the rims respectively to the front and rear ends of fittings 18 and 17, the rims do not lie in the same plane and accordingly will not foul one another when folded into their closed position (Figure 3).

For purposes of illustration, the planes of the two rims are shown as spaced from one another a greater distance than that usually found in practical embodiments of this frame.

55 By thus offsetting the planes of rim 10 and rim 11, lenses 12 and 13 may be readily folded one over the other into a superimposed position without exerting any twisting strains on bridge 16 or fittings 17 and 18, and, by the same token, the frame may be released into an open position more readily than if the lenses lay in the same plane when in open position. In order to hold the lenses together in closed position, I preferably provide a suitable latch 25 secured to rim 11 and projection 26 on rim 10 which will engage with latch 25 and so hold rims 10 and 11 in their closed position as more clearly shown in Figure 3.

A pair of parts 27 and 28 are respectively secured in any suitable manner to the abutting ends of rim 11. Part 27 is preferably joined to barrel 21 as at point 27a and has a threaded bore extending part way therethrough (not shown). Part 28 has a larger bore (not shown) 70 extending completely therethrough which re-

ceives a screw 29 which is in threaded engagement with the bore in part 27 to hold the ends of rim 11 together and to suitably hold lens 13 therein. Lens 12 is held within rim 10 by a substantially similar construction (Figure 1).

It will thus be seen that I have provided an oxford frame in which the lenses may be folded one over the other without materially engaging or fouling with one another during the folding operation. It will likewise be seen that the nose guards 19 and 20, being rigidly secured to bridge 16, are not displaced during the closing or opening of the rims 10 and 11, thus avoiding any risk of bothersome and damaging interference therebetween. Due to the relative ease with which my frame may be opened or closed, the whole assembly is adequately protected against breakage even with hard use. Accordingly the several objects hereinabove referred to as well as many others are successfully accomplished.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. In eyeglass construction, in combination, a substantially rigid bridge member, a pair of rigid nose guards immovably secured to said bridge member and extending downwardly and outwardly therefrom, a pair of rims pivotally secured to the ends of said bridge member in spaced parallel planes which planes are spaced from said nose guards, and means connected to said rims and said bridge member to hold said rims in extended relation whereby said rims may move free of each other and free of said nose guards into juxtaposed position without distortion of said bridge member when said rims are pivoted.

2. In eyeglass construction, in combination, a substantially rigid bridge member, a pair of rigid nose guards immovably secured to said bridge member and extending downwardly and outwardly therefrom, a pair of rims pivotally secured to the ends of said bridge member in spaced parallel planes, said planes being spaced from said nose guards, and springs connected to said rims and said bridge member to bias said rims in opposite directions whereby said rims may move free of each other and free of said nose guards into juxtaposed position without distortion of said bridge member when said rims are pivoted.

3. In eyeglass construction, in combination, a substantially rigid bridge member, a pair of rigid nose guards immovably secured to said bridge member and extending downwardly and outwardly therefrom, a pair of rims pivotally secured to the ends of said bridge member in spaced parallel planes which planes are spaced from said nose guards, springs connected to said rims and said bridge member to bias said rims in opposite directions whereby said rims may move free of each other and free of said nose guards into juxtaposed position without distortion of said bridge member when said rims are pivoted, and means on said rims limiting the outward movement of said rims with respect to said bridge member.

4. In eyeglass construction, in combination, a pair of rims, a substantially rigid bridge member having a pair of lugs at each end thereof, a pair of fittings, one of said fittings being secured to each of said rims and said fittings being offset

with respect to each other, a spring disposed in each of said fittings, pin means extending through said lugs and said fittings to pivotally mount said rims in spaced parallel planes to move free of each other into and out of a juxtaposed position, each of said springs being connected to one of

said lugs and one of said fittings to bias said rims in opposite directions, and a pair of rigid nose guards rigidly secured to said bridge member and spaced out of the path of movement of said rims.
